UNITED STATES PATENT OFFICE

2,299,495

DUAL AGENCY WASHER

William Rocke, South Bend, Ind.

Application September 1, 1939, Serial No. 292,973

5 Claims. (Cl. 68—53)

This invention relates to domestic washing machines and involves the addition of an exposed agitator washing means to my fluid agency washer as disclosed in my Patent Re. 20,424, reissued June 22, 1937.

The particular object of the invention is to provide two methods of washing in a domestic washer, the one effecting washing action by fluid agency alone and the other by exposed mechanical agency.

Another object is to provide means whereby clothes may be washed in a domestic washer by a gentle fluid agency or by an exposed mechanical agency or by a combination of the two agencies.

Other objects and benefits will be disclosed in the following descriptions and drawings in which:

Fig. 1 is a cross sectional elevation view of a washing machine employing my dual agency 20 washing means;

Fig. 2 is a broken enlarged cross sectional view of the mechanism of the washer shown in Fig. 1;

Fig. 3 is a similar view to Fig. 2 except showing an optional motor mounting and drive arrangement;

Fig. 4 is a broken enlarged cross sectional view of the top of the agitator post and agitator as shown in Fig. 3 but involving an optional driving mechanism which later will be explained;

Fig. 5 is an enlarged cross sectional elevational view of the mechanism similar to that shown in Fig. 3 except showing a modification wherein the impeller pumping means is omitted, as will later be explained; and

Fig. 6 is a broken elevation view similar to Fig. 2 except showing a modification of the impeller jet in its relation to the agitator, as will later be explained.

Now referring to the drawings, and at the outset particularly to Fig. 1, I show a conventional structure of a domestic washing machine wherein the tub 18 is mounted on a base ring 11 supported on legs 12. A mechanism gear case unit 13 driven by a motor 14 is supported on the base 11 in a conventional manner. Extending from the gear case 13 and supported by the base 11 is a conventional wringer post 15 supporting a wringer head 16 and a roll wringer 17.

Supported in the interior of the tub 18 is a hollow agitator post member 18, and surrounding this agitator post is a perforated plate 19 which separates the tub into an upper washing compartment and a lower water inlet compartment,

as is explained in detail in my Patent No. Re. 20,424, above mentioned. In the present structure I have mounted a revolving or oscillating agitator 22 on the agitator post 18, and as shown in Fig. 1, this agitator 22 is driven by the pinion 25 in the gear case 13 by conventional agitator drive mechanism wherein the pinion 25 is oscillated to transmit conventional oscillatory movement of the agitator 22. Also through the gear case 13 I drive the rotating pump mechanism by conventional transmission means ending in the belt and pulley mechanism 20 as shown. This mechanism is controlled by a clutch (not shown) in the gear case 13 which has the manual control means 21 available to the operator whereby the rotation of the pump impeller may be stopped and the washer run as a conventional agitator washing machine. In a similar manner the oscillation of the pinion 25 is controlled by conventional clutch means having a manual control lever 23 which provides means whereby the operator may control the oscillation of the agitator to stop it, whereby the washer would be operated as a washing machine having only a fluid agency washing action.

From the above description it will be understood that I provide in a domestic washing machine means whereby washing may be accomplished by conventional agitator means or by fluid action or by a combination of the two washing agencies. It is appreciated in the washing machine art that washing action by fluid alone is much easier on clothes and, therefore, lighter and more delicate fabrics may be washed with safety. Similarly it is recognized that the agitator action in domestic washing machines, although very effective for heavier and dirtier garments, is somewhat severe on the lighter garments. It will, therefore, be appreciated that by the combination above set forth the operator has a choice of the two methods, and further, by the combination of the two I have provided a new method which combines the features of the other two in a manner which gives optimum results.

Now referring to Fig. 2, I show an operating structure used to attain the results above described. As is clearly set forth in the drawings, the hollow agitator post 18 is supported on the tub 18 by conventional structure which is clearly illustrated in the drawings and which does not need detailed explanation. The agitator pinion 25 is fixed to the drive shaft 24 which is mounted in conventional bearing structure 30 and 30'. A splined torque drive 26 is pinned to the top of

the shaft 24 and makes splined connection with the internal spline member 27 affixed to the agitator 22 by the screw 28.

It will be appreciated that by this structure the agitator 22 may be lifted off of the agitator post 18 in the conventional manner. The driven pulley of the pulley transmission 20 is affixed to the tube 29 rotatably mounted in the bearing structure 30 to drive the pump impeller 31. The pump impeller 31 is so formed to lift the water 10 in the lower section of the tub 10 to drive it rapidly through the jets 32 in the base of the agitator post 18. The impeller 31, being driven at high speed, ejects a horizontal circular stream of water through the jets 32 and over the perforated plate 19 and up the side walls of the tub 10 in a circular manner which imparts to the liquid in the tub an annular radial revolving movement which has been found to be very effective in the washing of clothes. The perforations in the plate 19 are arranged to be of larger area than the capacity of the impeller 31 and, therefore, water is re-supplied to the sump and impeller 31 in a manner which does not interfere with the general radially revolving movement as above described. When clothes are inserted in the tub, they are turned and revolved in a vortex-like turbulent mass which without the action of the agitator are never touched by any mechanical means.

The additional action of the agitator 22 when used in conjunction with the fluid washing means has the effect of permitting heavier loading of clothes in the tub and more effective washing of heavier and dirtier garments. It has been found, however, that such agitator action combined with my fluid actuating means is not as destructive to the clothes as when the agitator is used alone, and thereby I attain an optimum washing result.

In Fig. 3 I show an alternative structure to that shown in Fig. 2 wherein the motor 14 drives the agitator shaft 24 directly and both the impeller 31 and the agitator 22 are revolved by the shaft 24 at the same time and in a similar manner. Although it has been found impossible to operate conventional agitators in this manner, the combination of the agitator washing means with my fluid action means makes this variation in structure possible and gives a new result.

In Fig. 4 I show a small compact gear case unit 33 mounted on the top of a revised agitator post structure 18' and driven by the same drive shaft 24. This compact gear case structure 33 has conventional gearing disposed therein whereby a driven stub shaft 34 is oscillated in a conventional manner. As shown in Fig. 4, I attach the stub shaft 34 to the stem of the agitator 22 by means of the Woodruff key 35 and the round head cap screw 36. By this structure I provide means whereby the drive shaft 24 driving the impeller 31 is capable of transmitting oscillatory movement to the agitator 22.

In Fig. 5, I show still another optional arrangement quite similar to that shown in Fig. 3, but wherein the impeller 31 is omitted. By this arrangement I drive the agitator 22 either in a continuous rotating manner by the structure as shown or in an oscillatory manner with a gear case, as shown in Fig. 4. It will be appreciated that the agitator 22 is actually an exposed pump vane structure and that the vanes on this agitator will act as a pump. Positioned as it is over the perforated plate 19 and adjacent to the jets 32, the operation of this agitator results in water

currents which by the injector principle induces currents from the sump under the perforated plate 19 whereby a different washing water action is created. It will be appreciated that the jets 32 in relation to the base 22' of the agitator may be changed; for instance, as shown in Fig. 6, whereby variable water current results may be attained by this variation in the jets and their relative locations which effect different ejected currents.

Now referring to Fig. 6, I show a variation in the structure as outlined and explained for Fig. 2. The hollow agitator post 18 has been changed to the structure shown as 18' wherein the jets 32 have been changed as shown at 32' to register with similar outlet jets 32'' in the base 22' of the agitator. It now will be appreciated that the impeller 31 will drive currents of water through the jets 32' and 32'' over the base 22' of the impeller. It will be appreciated that these jets of water being discharged over the base of the impeller will have the effect of rapidly removing and throwing from the impeller any clothing which might be lodged on the impeller vane. Inasmuch as clothes damage generally is a result of clothes lodging on the vanes and being jerked backward and forward, this revised structure has the effect of reducing clothes damage from the impeller to a still greater extent than the structure shown in Fig. 2, and thereby the combination of mechanical and liquid washing means is made still more effective.

From the above description it will be appreciated that I have combined my fluid washing means with the conventional agitator means in a manner which permits the housewife to use either one or the other as the need arises, and further, that by the combination of the two methods I attain new and more beneficial results not found in either the liquid or the mechanical washing methods. It is appreciated that although I have shown certain variations in structure that other variations are possible and even contemplated. However, I do not wish to be constrained or limited to the structure shown except as such limitations are imposed by my claims.

I claim:

1. In a fabric washing machine the combination of a tub, said tub being divided into a washing compartment and a sump by a perforate partition, a hollow agitator post mounted centrally within the tub having a water intake opening connected with the sump and a circular discharge orifice leading into the washing compartment above and adjacent to the perforate partition, an agitator mounted on the post above the circular discharge orifice, an impeller pump mounted within the tub below the partition having a water intake connected with the sump and a discharge through the agitator post orifice, means to drive the pump at high rotational speed, and gear mechanism to oscillate the agitator, whereby dual mechanical and fluid washing means is provided.

2. In a fabric washing machine the combination of a tub, said tub being divided into a washing compartment and a sump by a perforate partition, a hollow agitator post mounted centrally within the tub having a water intake opening connected with the sump and a circular discharge orifice directed into the washing compartment above and adjacent to the perforate partition, an agitator having vertical blades mounted on the post above the circular discharge orifice, and an impeller pump mounted within the tub below

the partition, concentric with the agitator post and having a water intake connected with the sump and a discharge through the agitator post orifice.

3. In a fabric washing machine the combination of a tub, said tub being divided into a washing compartment and a sump by a perforate partition, a hollow agitator post mounted centrally within the tub having a water intake opening connected with the sump and a circular discharge orifice leading into the washing compartment above and adjacent to the perforate partition, an impeller pump mounted within the tub below the partition having a water intake connected with the sump and a discharge through the agitator post orifice, an agitator mounted on the post having a base covering the circular discharge orifice, holes in said base contiguous to the orifice permitting discharge of water currents from the pump over the base, means to drive the pump at high rotational speed, and gear mechanism to oscillate the agitator, whereby dual mechanical and fluid washing means is provided.

4. In a fabric washing machine the combination of a tub, said tub being divided into a washing compartment and a sump by a perforate partition, an impeller pump including a housing mounted centrally in the bottom of the tub below the partition, means to removably support the perforate partition from the pump housing in-

cluding a hollow agitator post mounted on the housing, a vaned agitator mounted on the post, a circular pump discharge orifice through the agitator post above the partition, means to drive the pump at high rotational speed, and gear mechanism to oscillate the agitator, whereby dual mechanical and fluid washing means is provided.

5. In a fabric washing machine the combination of a tub, said tub being divided into a washing compartment and a sump by a perforate partition, a hollow agitator post mounted centrally within the tub having a water intake opening connected with the sump and a circular discharge orifice leading into the washing compartment above and adjacent to the perforate partition, an impeller pump mounted within the tub below the partition having a water intake connected with the sump and a discharge through the agitator post orifice, an agitator mounted on the post having vanes extending beyond the discharge orifice in the area traversed by water currents from the pump, means to drive the pump at high rotational speed, a gear mechanism to oscillate the agitator whereby dual mechanical and fluid washing means is provided with the water currents from the pump discharged over the vanes of the agitator to prevent the clothes sticking on the vanes with consequent damage to the clothes.

30

WILLIAM ROCKE.
